Application October 21, 1938, Serial No. 236,146
In Great Britain October 22, 1937

2 Claims. (Cl. 179—171)

The present invention relates to thermionic valve amplifiers of the type in which negative feedback is employed to reduce amplitude distortion and to render the amplification less dependent upon changes in polarising voltages and valve characteristics.

When amplifiers of this type are employed for the amplification of signals comprising a wide band of frequencies, such as television signals, it is found that stray capacity associated with the output circuit reduces the amplification at the higher frequencies. It has been proposed in the specification of British Patent No. 465,118 to shunt the cathode resistance employed for feedback purposes with a condenser, the time constant of the resistance and condenser being so chosen that it is approximately equal to the time constant of the anode load resistance and the stray capacity. This has the effect of maintaining the amplification constant to a higher frequency than it would be if no condenser were used, but for very high frequencies the impedance of the condenser falls to such a low value that it is no longer large compared with the inverse of the mutual conductance of the valve which condition is necessary if the amplification is to be maintained substantially constant for the very high frequencies encountered in television signals.

It is the object of the present invention to overcome this difficulty so that the amplification may be maintained substantially constant up to a higher frequency than would otherwise be possible.

According to the invention a thermionic valve amplifier is provided of the kind comprising a thermionic valve having an output impedance which is substantially equivalent to a resistance shunted by a capacity and a feedback impedance including a capacity in shunt and so arranged as to afford negative feedback so as to increase the frequency range over which substantially uniform amplification occurs and wherein there is provided in series with the capacity included in said feedback impedance an inductance the value of which is so chosen as to further increase the frequency range over which substantially uniform amplification occurs.

More specifically, the invention comprises a thermionic valve amplifier of the kind comprising a thermionic valve having an output impedance in its anode circuit which is substantially equivalent to a resistance shunted by a capacity and a feedback resistance in the cathode circuit of said valve so connected that the voltage set up across said resistance is effectively applied in antiphase to the control electrode of said valve, said feedback resistance being shunted by a capacity so as to increase the frequency range

over which substantially uniform amplification occurs and wherein there is provided in series with the capacity shunting said feedback resistance an inductance the value of which is so chosen as to further increase the frequency range over which substantially uniform amplification occurs. 5

In order that the invention may be clearly understood and readily carried into effect it will now be more fully described with reference to the accompanying drawing in which:

Figure 1 illustrates in conventional form an amplifier constructed in accordance with the preferred embodiment of the invention with the feedback impedance in the cathode circuit of the valve, the sources of the anode current, grid voltage, etc., being omitted for simplicity, and

Figure 2 is an explanatory figure.

The amplifier as shown in Figure 1 comprises a thermionic valve 1 having four electrodes, namely, the cathode 2, control grid 3, the screen grid 4 and the anode 5. The cathode is connected to earth via resistance R_c shunted by inductance L_c and condenser C_c in series, which constitute the negative feedback impedance Z_c . The control grid 3 is connected to earth via the source of input voltage V_1 which is to be amplified. The screen grid 4 is connected to a source of constant voltage, not shown, whilst the anode is connected to the output resistance R_a , which is returned to earth. The condenser C_a in parallel with resistance R_a represents stray capacity, which may be due, for example, to further apparatus receiving the amplified output voltage V_2 developed across resistance R_a . With a sinusoidal input voltage V_1 , let the alternating current through the cathode impedance Z_c be i_c and the alternating output voltage across resistance R_a be V_2 . Since the valve 1 is of the screen grid type, it will have a high internal resistance, so that the current flowing through the valve will be substantially independent of the external anode circuit impedances and will be determined by the input voltage between grid and cathode. If g is the mutual conductance as between grid and cathode of the valve 1, we have $i_c = g (V_1 - i_c Z_c)$. 30 35 40 45

Thus

$$i_c(1+gZ_c) = gV_1 \quad 50$$

or

$$i_c = \frac{V_1}{Z_c + \frac{1}{g}} \quad (1) \quad 55$$

We also have

$$V_2 = k i_c Z_a \quad (2)$$

where Z_a is the impedance between the anode 5 and earth and k is a constant representing the 60

proportion of the current leaving the cathode and reaching the anode through the screen.

From Equations 1 and 2 we have

$$5 \quad V_2 = \frac{kZ_a}{Z_c + \frac{1}{g}} \cdot V_1$$

Now

$$10 \quad Z_a = R_a \left(\frac{1}{1 + j\omega C_a R_a} \right)$$

and

$$15 \quad Z_c = R_c \left(\frac{1}{1 + j\omega C_c R_c} \right)$$

Therefore we have

$$20 \quad V_2 = \frac{kR_a \left(\frac{1}{1 + j\omega C_a R_a} \right) V_1}{R_c \left(\frac{1}{1 + j\omega C_c R_c} \right) + \frac{1}{g}}$$

Now V_2 can be made substantially constant over a range of frequencies in known manner by making $C_c R_c = C_a R_a$, but at high frequencies 25 since

$$30 \quad V_2 = \frac{\frac{1}{j\omega C_a}}{\frac{1}{j\omega C_c} + \frac{1}{g}} V_1$$

it follows that V_2 will only remain constant so long as

$$\left(\frac{1}{j\omega C_c} + \frac{1}{g} \right)$$

35 is substantially inversely proportional to frequency.

This condition is satisfied so long as

$$40 \quad \frac{1}{\omega C_c} > \frac{1}{g}$$

but this condition is clearly not satisfied when the impedances of C_c falls to equality with

$$45 \quad \frac{1}{g}$$

and for frequencies greater than

$$\frac{\omega_0}{2\pi}$$

50 where

$$\omega_0 = \frac{g}{C_c}$$

55 V_2 will therefore fall below its constant value for lower frequencies.

By inserting an inductance in series with the condenser C_c the denominator in the above expression for V_2 can be caused to vary substantially inversely with frequency up to frequencies 60 higher than

$$\frac{\omega_0}{2\pi}$$

and it can be shown that particularly good results are obtained when the inductance has a value

$$L = \frac{1}{2} C_c \left(\frac{1}{g} \right)^2$$

in which case the output voltage V_2 will remain substantially constant up to a frequency

$$\frac{2\omega_0}{2\pi}$$

A curve illustrating the nature of this improvement is shown in Figure 2, in which curve (a) is the characteristic obtained with no inductance inserted in the cathode circuit, while curve (b) is that characteristic obtained when an inductance of magnitude

$$\frac{1}{2} C_c \left(\frac{1}{g} \right)^2$$

is connected in series with the condenser C_c .

Although the invention has been described 15 with reference to screen grid valves, it will be obvious that pentode valves or any other high impedance valves having screen grids may equally well be used.

We claim:

1. A thermionic valve amplifier of the kind comprising a thermionic valve having an output impedance which is substantially equivalent to a resistance shunted by a capacity and a feedback impedance including a capacity in shunt 25 and so arranged as to afford negative feedback so as to increase the frequency range over which substantially uniform amplification occurs, the limiting frequency of said range being $\omega_0/2\pi$, and wherein there is provided in series with the 30 capacity included in said feedback impedance an inductance the value of which is so chosen as to further increase the frequency range over which substantially uniform amplification occurs, the limiting frequency of said latter range 35 being approximately $2\omega_0/2\pi$, the value of said inductance being equal to

$$\frac{1}{2} C_c \left(\frac{1}{g} \right)^2$$

where C_c is the value of the condenser in shunt to the feed-back impedance and g is the mutual conductance of the valve.

2. A thermionic valve amplifier of the kind comprising a thermionic valve having an output impedance in its anode circuit which is substantially equivalent to a resistance shunted by a capacity and a feedback resistance in the cathode circuit of said valve so connected that the voltage set up across said resistance is effectively applied in antiphase to the control electrode of said valve, said feedback resistance being shunted by a capacity so as to increase the frequency range over which substantially uniform amplification occurs and wherein there is provided in series with the capacity shunting said feedback resistance an inductance the value of which is so chosen as to further increase the frequency range over which substantially uniform amplification occurs, the value of said inductance being equal to

$$\frac{1}{2} C_c \left(\frac{1}{g} \right)^2$$

where C_c is the value of the condenser in shunt to the feed-back resistance and g is the mutual conductance of the valve.
